[57] CLAIM

The ornamental design for an aerial toy, as shown and described.

DESCRIPTION

FIG. 1 is a side elevational view of an aerial toy showing my new design;

FIG. 2 is a side elevational view of the side opposite that shown in FIG. 1;

FIG. 3 is a front perspective view thereof;

FIG. 4 is a rear elevational view thereof;

FIG. 5 is a front elevational view thereof.
